FIG. 1

FIG. 2

INVENTOR
Mellicent Rogers Belcom
BY Samuel Stephen Barker
ATTORNEY

UNITED STATES PATENT OFFICE

130,930

DESIGN FOR AN EMBLEM PIN

Millicent Rogers Balcom, Claremont, Va., assignor to Medical and Surgical Relief Committee of America

Application October 24, 1941, Serial No. 103,880

Term of patent 3½ years

To all whom it may concern:

Be it known that I, Millicent Rogers Balcom, a citizen of the United States, residing in the city of Claremont, county of Surry, State of Virginia, have invented a new, original, and ornamental Design for an Emblem Pin, of which the following is a specification, reference being had to the accompanying drawing, forming a part thereof.

Fig. 1 is a front elevational view of an emblem pin showing my new design;

Fig. 2 is a side view thereof;

Fig. 3 is a top view thereof.

I claim:

The ornamental design for an emblem pin, substantially as shown.

MILlicent ROGERS BALCOM.
